UNITED STATES PATENT OFFICE

HENRY O. COSTELLO, OF PROVIDENCE, RHODE ISLAND

DISPLAY TOY

Application filed October 25, 1929. Serial No. 402,368.

This invention relates to an improved toy comprising a movably supported disk having one side thereof divided into sections, and the several sections being of different colors, so that as the disk is caused to rotate at varying speeds certain of the colors will have the appearance of blending together or moving over the surface of the disk, thereby producing a novel and pleasing effect upon the eye of an observer.

One object of the invention is the provision of a novel toy of the character described wherein the disk is supported by a cord member in such a manner as to be freely rotatable in a substantially horizontal plane, and wherein the cord member is capable of being twisted to store up potential energy for rotating the disk.

Another object of the invention is the provision of a device of this character wherein one surface of the disk is divided into sectors, certain of which are made up of differently colored concentric bands, whereby, upon rotation of the disk, the colors of the several bands blend together to present the appearance of solid colored bands, the colors of the bands being so arranged that the several bands are distinguishable from each other.

A further object of the invention is the provision of a device of this character wherein the colored surface of the disk is divided into sections, each of which is made up of differently colored concentric bands, together with means for varyingly concealing certain of said sectors from view, whereby the concentric bands are caused to change in color as viewed by an observer during the rotation of the disk, and the several bands appear to be made up of solid colors due to the blending of the colors as the disk is rotated.

Another object of the invention is the provision of a device of this character having an elastic cord supporting member adapted to be secured to the center of the disk and capable of being twisted to store up energy for imparting rotative movement to the disk, whereby the speed of rotation of the disk may be varied through the elasticity of the supporting cord member to bring out additional variations of the color changes as seen by an observer.

Other objects and advantages of the invention relate to various improved details of the structure and different arrangements of the parts as will be more fully set forth in the detailed description to follow.

Referring to the drawings:

Fig. 1 is a perspective view of one form of the improved structure illustrating the position of the parts when the supporting cord member is held by the hand of an observer, and showing the normal position of one form of colored disk as rotatably supported by the cord member, and,

Fig. 2 is a distorted perspective view of a modified form of the structure wherein one surface of the disk is divided into sectors, and each sector made up of differently colored concentric bands, and a vane member mounted in proximity to the colored surface of the disk and adapted to move over the surface of the disk at a speed less than the speed of rotation of the disk.

In the embodiment of the invention illustrated in Fig. 1 of the drawings a disk 1 has a supporting cord member 2 secured to the center thereof, the opposite end of said supporting cord member being secured to a ring 3 which may be held by the finger of an observer.

One surface of the disk 1 is divided into sections, as indicated by reference characters 4, 5, 6, 7, 8 and 9, each of said sections being colored and the color of each section differing from the colors of the sections next adjacent thereto. In the embodiment illustrated herewith the section 4 is colored green, the section 5 is purple, the section 6 is orange, the section 7 is blue, the section 8 is yellow, and the section 9 is red. Any other suitable or desired arrangement of the colors may be employed, and the colored sections of the disk may be differently shaped and arranged as may be found desirable in practice.

The supporting cord 2 may be formed of any suitable or desired elastic or non-elastic material which is capable of being twisted to store up potential energy for imparting

rotation to the disk 1, and may be formed from a single strand or from a plurality of strands capable of winding about each other when twisted to impart rotation to the disk. 5 I find it preferable, however, to employ an elastic supporting cord which may be a solid rubber strip adapted to wind upon itself and thus store up energy for imparting rotation to the disk, since in the use of an elastic supporting cord the disk may be caused to oscillate longitudinally of the supporting cord, as indicated by the dotted line position of the disk 1, in addition to its rotative movement about its center.

15 In the operation of the device shown in Fig. 1, the disk 1 may be rotated by hand in one direction, or a twist may be imparted to the supporting cord member 2 in any desired manner in order that when the disk is released it will rotate rapidly about its center, thus causing the colors on the surface of the disk 1 to blend together and appear to move across the surface of the disk as viewed by the eye of an observer.

20 In the embodiment of the invention as illustrated in Fig. 2 of the drawings, a disk 10 has one surface thereof divided into sectors 11, which are indicated as separated from each other by dividing lines 12 for the purpose of better illustrating the invention, although in practice the lines separating the various colors serve as dividing lines for indicating the sector sections. A supporting cord member 15, similar to the supporting cord member 2 previously described, has one end secured to the center of the disk 10, and the opposite end thereof may be secured to a ring 3 as shown in Fig. 1.

25 A vane member 16 may be positioned upon and in close proximity with the colored surface of the disk 10, and the vane member is provided with a central opening 17 to receive the supporting cord member 15, and oppositely positioned wings 18, each of which is of substantially the same area as one of the sectors 11. The central portion 19 of the vane member 16 may be depressed somewhat to rest upon and permit the same to rotate freely relative to the disk 10.

30 The sector portions 11 of the disk are each made up of a plurality of concentric bands 20, 21, 22 and 23, that portion of each band which is located within one sector being colored differently from that portion of the band located within the sectors next adjacent thereto.

35 When the disk 10 is rotated rapidly in a substantially horizontal plane the several colors making up each of the concentric bands 20, 21, 22 and 23 blend together to give the appearance to the eye of an observer of each being made up of solid colors. The vane member 16 tends to rotate about the supporting cord member, but at a rate of speed considerably slower than the disk, and spasmodic

movement of the vane member relative to the disk may be occasioned during the rotation of the disk by causing the disk to move up and down through the elasticity of the cord member, when the cord used is of an elastic character. This movement of the vane member over the face of the disk 10 causes the solid colors of the concentric bands 20, 21, 22 and 23 to change as the wings 18 of the vane member moves from certain sectors to others to conceal certain of the colors making up the concentric bands. 70 75

This rotation of the vane member at a rate of speed less than that of the disk is brought about by reason of the fact that only a small portion of the vane member, namely, the depressed portion 19, is in engagement with the face of the disk, and by reason of the fact that the opening in the vane member is of such size that the edges adjacent the opening 80 85 engage the edges of the cord member, as shown in Fig. 2 of the drawings, to somewhat retard the movement of the vane member relative to the cord member.

90 In this manner, the concentric bands on the disk 10, appear to the eye of an observer to be each made up of solid colors, and these colors appear to change as the disk 10 rotates about its center, giving the disk a novel and pleasing appearance. 95

95 In this form of the structure, the vane member, may, of course, be omitted, if desired, and the disk will then give the appearance of the concentric bands being each made up of solid colors, but its inclusion imparts the additional novel effect of causing the color of each band to appear to change during the rotation of the disk. 100

105 The various colors shown as making up the concentric bands 20, 21, 22 and 23 may be varied from those shown in the drawings as may be desired, and the vane member may be given a shape different from that illustrated, although the shape of the wings 18 as shown herein is well adapted for the purpose of obscuring from view the colors of the sector sections as the vane member travels over the colored surface of the disk. 110

115 The operation of the structure shown in Fig. 2 of the drawings is similar to that previously described except that in the arrangement of colored sections as shown in Fig. 2, the concentric bands 20, 21, 22 and 23 present the appearance, when rotated, of being formed of solid colors, and when the vane member 16 is employed, the vane member tends to move slowly over the face of the disk as the disk is rotated, thus progressively concealing from view certain of the sectors, and causing the concentric bands to present the appearance of changing in color during the rotation of the disk. 120 125

130 The vane member 16 may be given any desired color or arrangement of colors and instead of being of the shape illustrated in

Fig. 2 of the drawings, may be made of any desired circular or non-circular shape, and such circular or non-circular member may be mounted either concentrically or eccentrically with reference to the supporting cord member, and may be employed in connection with the disk 10 of Fig. 2 or the disk 1 of Fig. 1, or any other desired arrangement of colors as may be desired. Instead of one face of the disks 1 and 10 being colored as previously described one or more separate thin disk members may be employed and separately positioned upon a plane supporting disk in order to permit the employment 15 of a plurality of varying color designs according to the wish of the user.

What I claim is:—

1. An article of manufacture comprising a disk having one side thereof divided into sectors, each of said sectors comprising a plurality of concentric colored bands, the corresponding band of one sector differing in color from that of the same band in one or more of the other sectors, an elastic cord member having one end secured to said disk for supporting the same in a horizontal plane, said cord being capable of being twisted whereby it will impart rotative movement to said disk and cause the colors making up each 30 of the several concentric bands, to blend and produce the effect upon the eye of an observer of uniformly colored concentric bands, and a vane member having a limited portion of its surface engaging said disk and rotatably 35 mounted upon said cord in frictional engagement therewith whereby upon rotation of said disk said vane member will rotate at a different speed than said disk to progressively 40 conceal from view the colors of certain sectors whereby the concentric colored bands are given the appearance of changing color during the rotation of the disk.

2. An article of manufacture comprising a disk having one side thereof divided into sectors, each of said sectors comprising a plurality of concentric colored bands, the corresponding band of each sector differing in color from that of the same band in one or more of the other sectors, an elastic cord member having one end secured to said disk for supporting the same in a horizontal plane, said cord being capable of being twisted whereby it will impart rotative movement to said disk and cause the colors making up each of the several concentric bands to blend and produce the effect of solid colors, and a vane member having a central depressed portion engaging said disk and movable upon rotation of said disk 55 at a rate of speed less than the speed of rotation of said disk to progressively conceal from view the colors of certain sectors whereby the concentric colored bands are each given the appearance of changing color during the 60 rotation of said disk.

3. An article of manufacture comprising a disk having one side thereof separated into a plurality of vari-colored sections, each of said sections differing in color from that of the section located next adjacent thereto, an elastic cord member having one end thereof secured to said disk for supporting the same in a horizontal plane, said cord being capable of being twisted whereby it will impart rotative movement to said disk, and a sector shaped vane member threaded upon said cord for rotation therearound and provided with a central depressed portion adapted to rest upon the colored surface of said disk and rotate relative thereto but at a speed less than the speed of rotation of said disk as the disk is rotated either through impulses imparted thereto exteriorly of said cord or through the twisting and untwisting of said cord, whereby the movement of said vane relative to the colored surface of the disk will effect changes in the appearance of the colored portion of the disk as viewed from the eye of an observer.

In testimony whereof I have affixed my signature.

HENRY O. COSTELLO.
